UNITED STATES PATENT OFFICE.

ISAAC N. GROVES, OF CLIO, TEXAS.

MECHANICAL MOTOR.

SPECIFICATION forming part of Letters Patent No. 307,853, dated November 11, 1884.

Application filed August 28, 1884. (No model.)

To all whom it may concern:

Be it known that I, ISAAC N. GROVES, a citizen of the United States, residing at Clio, in the county of Brown and State of Texas, 5 have invented certain new and useful Improvements in Mechanical Motors, of which the following is a specification, reference being had thereto in the accompanying drawing.

My invention has relation to mechanical 10 motors, and its object is to convert a given rotary into a vertical reciprocating motion, and to provide means whereby the stroke of the reciprocating motion may be increased or diminished, according to the use or work to 15 which the machine may be applied; and to these ends the novelty consists in the construction, combination, and arrangement of the same, as will be hereinafter more fully described, and particularly pointed out in the 20 claim.

The figure in the drawing is a perspective elevation of my improved motor.

A, A' are the sides, provided with legs a, which constitute the frame-work of the machine. B is the main driving-shaft, having crank b for operating the same. C is a gear-wheel centrally secured to said shaft, so as to mesh with the pinion D, secured to a secondary shaft, (not shown,) on the outer end of which 25 is a face-plate, E, having crank-pin holes c

located at different distances from the center. F is a removable screw crank-pin, which engages the lower end of the pitman G, its upper end being attached to the rear end of the lever H. This lever is fulcrumed in the adjustable standard I, and its forward end, i, is bifurcated to receive the end of the reciprocating bar K, which works in a guide, n, in the arm N, secured to the frame. The lever H is provided with a series of fulcrum-holes, h, 35 by means of which the stroke of the end i may be increased or diminished as the lever is adjusted, and the standard I may be adjusted to one of the series of holes o in the frame, so as to obtain greater or less power on the lever. 40

Having thus described my invention, what I claim as new and useful, and desire to secure by Letters Patent of the United States, is—

The combination, with the frame A, shaft B, gear C, pinion D, face-plate E, and pitman G, of the adjustable lever H o, standard I, and the reciprocating bar K, working in the guide-arm N, constructed and arranged substantially as and for the purpose set forth. 50

In testimony whereof I affix my signature in presence of two witnesses.

ISAAC N. GROVES.
